CLAIM

The ornamental design for a fuel dispenser, as shown and described.

DESCRIPTION

FIG. 1 is a front elevation view of a fuel dispenser showing our new design;

FIG. 2 is a right and left side elevation view thereof; and

FIG. 3 is a top plan view thereof, wherein the fuel dispenser hose members are fragmentarily shown for convenience of illustration.

The undisclosed rear portions of the fuel dispenser are a mirror image of those portions illustrated in FIG. 1 on the drawing.

FIG. 2

FIG. 1

FIG. 3
